CONTROL CIRCUIT FOR TELEPHONE
EXTENSION SIGNALS AND THE LIKEJohn H. Wheelock, Fitzwilliam, N. H., assignor to
Signal Engineering & Manufacturing Company,
New York, N. Y., a corporation of Massachusetts

Application June 14, 1943, Serial No. 490,744

12 Claims. (Cl. 179—81)

The present invention relates to an improved control arrangement for employing telephone ringing current to lock an electrical circuit in a given signalling status, until released by transient telephone talking current obtained through the removal of a conventional receiver from its hook, or until released automatically after a predetermined lapse of time in the event that the receiver is not removed.

While the standard ringer is adequate in ordinary telephone installations to signal an incoming call, it is desirable in many instances to employ an auxiliary signal of an audible or visual character that will attract attention to an incoming call in locations where the standard ringer cannot be heard. Such auxiliary signals are usually energized from a commercial power source through the operation of a telephone extension relay responsive to telephone ringing current.

When a telephone extension relay is energized by ringing current, it closes and completes a circuit from a suitable power source to the extension signal, such as a loud sounding horn, gong, or lamp, and in most instances it is desirable to have the extension signal remain continuously energized until the person called answers the telephone. To this end, telephone extension relays have heretofore been provided with various types of mechanical latching devices which serve to lock up the relay armature in response to the first application of ringing current and so maintain the circuit of the extension signal. Heretofore, such mechanical latching devices have been released by a manual operation so as to deenergize the extension signal when the person called answers the telephone; consequently the extension signal will remain energized in the event that the person answering neglects to perform the unlatching operation, or does not answer the telephone.

According to the present invention, there is provided an improved circuit arrangement for the control of telephone extension signals, whereby the removal of a conventional telephone receiver from its hook at the station with which the extension signal is associated will automatically bring about the release of the telephone extension relay in response to the flow of transient telephone talking current. In thus employing the talking current for the releasing action, the circuit is so arranged that the presence of the release winding in no way interferes with the flow of talking current to and from the telephone instrument. Furthermore, the circuit provides

means for automatically releasing the telephone extension relay in the event that the receiver is not lifted after the lapse of a predetermined period of time measured from the receipt of the initial impulse of ringing current to energize the signal. The above and other advantageous features of the invention will hereinafter more fully appear from the following description considered in connection with the accompanying drawings,

10 in which—

Fig. 1 is a schematic view, illustrating the circuit arrangement of the present invention, with the telephone extension signal in its non-operating condition.

15 Fig. 2 is a schematic view showing locking up of the extension signal, with the telephone receiver still down.

Fig. 3 illustrates release of the extension relay, with the receiver partially lifted.

20 Fig. 4 illustrates the condition of the circuit with the receiver fully lifted for the transmission of voice currents.

Fig. 5 illustrates means for automatically releasing the extension relay upon lapse of a predetermined time interval, with the receiver still unlifted.

25 Fig. 6 is a schematic view similar to Fig. 1, illustrating a modification of the circuit arrangement.

30 Fig. 7 is a detail showing the mounting of the hook-controlled contacts within the base of a telephone subscriber's set.

Fig. 8 is a plan view of the contacts shown in Fig. 7.

35 Referring first to Fig. 1, the invention is shown for purposes of illustration as being employed in connection with the conventional apparatus usually installed with a telephone subscriber's set, including a bell B, transmitter TR and receiver R.

40 The incoming line to the subscriber's set is indicated by the conductors L—1 and L—2, with these conductors serving to convey either ringing current to operate the bell B or talking current to and from the receiver R and transmitter TR respectively.

45 As previously pointed out, the object of the present invention is to provide a circuit arrangement for the control of a telephone extension signal and to this end the circuit includes a telephone extension relay 1 having an operating winding 2, the terminals of which are connected across the line conductors L—1 and L—2 in series with a condenser C. The relay 1 also comprises a pivotally mounted armature 3 carrying a contact 4 movable with respect to a stationary con-

tact 5. An extension signal S, such as a loud sounding bell or horn, or if desired a lamp, is adapted to be operated from a separate source of electrical energy, such as commercial power mains 6, through engagement of the contact 5 by the relay-operated contact 4.

Therefore, with the arrangement described thus far, telephone ringing current coming in over L-1 and L-2 will cause ringing of the bell B, as well as operation of the signal S through pulling in of the relay 1 to close the contacts 4 and 5 as indicated in Fig. 2.

In order to hold in the relay 1 after the first impulse of ringing current and thereby maintain the extension signal S in signalling status, the relay 1 provides a latch 7. This latch 7 is pivoted at 8 and provides a notch 9 adapted to fit under the end of relay armature 3 when the latter is moved from the position of Fig. 1 to the position of Fig. 2. The latch 7 provides a trip arm 10 which, when the latch is in the position of Fig. 1, tends to turn the latch about its pivot 8 as soon as the free end of the armature 3 enters the notch 9 in response to pulling in of the armature 3 by the winding 2. Therefore, whenever the extension signal relay 1 is energized by ringing current, the armature 3 will be automatically locked in its attracted position to maintain the signal S continuously energized from the power mains 6 through closed contacts 4 and 5, and thereby call attention to the fact that an incoming call should be answered at the telephone subscriber's set, as represented by the receiver R and transmitter TR.

In order to automatically unlatch the relay 2 in response to removal of the receiver R to answer the call, the relay 1 further provides a trip coil 11 located beneath the trip arm 10. The coil has a magnetic plunger 12 associated therewith, with the lower end of the plunger resting against a stop 13 so that a portion of the plunger is outside of the coil. Therefore, energization of the trip coil 11 will tend to draw the plunger 12 upwardly to engage the trip arm 10 and so exert a turning force on the latch 7 tending to move the notch 9 away from the end of the relay armature 3.

One terminal of the trip coil 11 is connected to the line conductor L-1 in series with the winding 14 of the receiver R, while the other terminal thereof is connected to a contact 15, normally spaced from the hook 16 of the telephone receiver R. The hook is movable and is illustrated diagrammatically as being held down away from the trip coil contact 15 by the weight of the receiver R. The hook has also associated therewith contacts 17 and 18 respectively connected to the receiver winding 14 and to a winding 19 of the transmitter TR. The several contacts 15, 17 and 18 are different distances from the hook 16, and since the hook itself is connected to the other line conductor L-2, upward movement of the hook upon removal of the receiver R will bring about a sequence of operations, resulting in silencing the extension signal S in advance of carrying on a conversation at the subscriber's set.

Assuming that ringing current has caused locking up of the relay 1 to energize the extension signal S, as shown in Fig. 2, it is evident that signal S will be maintained in its signalling status as long as the receiver R holds down the hook 16. However, when anyone starts to answer the incoming call at the subscriber's set by lifting the receiver R, the resulting upward movement of the hook 16 almost immediately engages the contact

15 which, as hereafter described, is yieldable with respect to the hook. When this occurs, the trip coil 11 is connected across the line conductors L-1 and L-2 in series with the receiver winding 14 and the resulting flow of transient talking current energizes the trip coil 11. This results in pulling up the plunger 12 to engage the trip arm 10 and thereby turn the latch into the position of Fig. 3. Since the relay winding 2 is then de-energized, the armature 3 is free to fall and thereby cause disconnection of the extension signal S from the mains 6 as the contacts 4 and 5 are disengaged.

Completion of the upward movement of the hook 16 causes the contacts 18 and 17 to be engaged in that order, thereby connecting first the transmitter winding 19 and then the receiver winding 14 across the line conductors for the transmission of voice currents. It is to be noted that with the hook 16 engaging both contacts 15 and 17, the relay trip coil 11 will be short-circuited and therefore will have no disturbing effect on the transmission of voice currents to and from the subscriber's set. When, upon completion of the telephone conversation, the receiver R is replaced on its hook 16, all of the circuits will be restored to the condition of Fig. 1, with the telephone extension relay 1 in non-signalling status and with the trip coil 11 entirely removed from the circuit of the subscriber's set, so that the entire arrangement is in readiness to signal an incoming call in response to the next succeeding impulse of ringing current.

As previously pointed out, the invention also provides means for releasing the telephone extension relay in the event that the receiver is not lifted after the lapse of a predetermined period of time, measured from the receipt of the initial impulse ringing current to operate the signals. Such an arrangement is shown in Fig. 5, in which elements of the circuit common to Fig. 1 are designated by like reference characters, inasmuch as these elements function in the same manner as described with reference to Fig. 1, should the receiver be lifted while the time interval is still running.

Referring to Fig. 5, it will be noted that the terminal of the coil 11, which is connected to the hook contact 15, is also connected to a yieldable contact 20 that is normally separated from a contact 21 connected to the line conductor L-2. A thermal element 22, indicated as being of the bimetal type, is associated with the contact 20, so that when the element 22 is at ordinary room temperature, an insulating button 22a of the element is just bearing on the contact 20.

A heating coil 23 for the element 20 has one terminal connected to one power main 6 in common with the relay contact 4, while the other terminal thereof is connected to an extra contact 24 of the relay 1 adjacent to the extension signal contact 5. Therefore, closure of the contacts 4 and 5 to operate the extension signal S, as indicated in dotted lines in Fig. 5, will also result in connecting the heating coil 23 across the mains 6.

Assuming that an impulse ringing current has locked the relay 1 in signalling status and that no one lifts the receiver at the subscriber's set in order to answer the call, the heat generated by the coil 23 will cause the expanding thermal element 22 to swing laterally and slowly move the contact 20 in the direction of the contact 21. This movement continues until, after the lapse of a predetermined time interval governed by the

design of the element, the contact 20 will engage the contact 21, thereby connecting the trip coil 11 to the line conductor L-2, with the resulting flow of transient talking current serving to unlatch the extension relay 1. In other words, closure of contacts 20 and 21 has the same result as upward movement of the hook 16 to engage the contact 15, as previously described with reference to Fig. 3.

As soon as the relay 1 drops back to disengage the relay contact 4 from the contact 24, the resulting cooling and contraction of the thermal element 22 will permit separation of the contacts 20 and 21, thereby disconnecting the trip coil 11 from line conductor L-2 and restoring the entire circuit to its normal non-signalling status. Obviously, other types of time delay devices can be employed to cause automatic release of the extension relay after the lapse of a predetermined interval following the receipt of an impulse of ringing current.

Referring now to Fig. 6, there is shown a modified circuit arrangement whereby the trip coil 11 is adapted to be only momentarily energized by talking current independently of the receiver winding 14, the trip coil being thereafter entirely shunted out of the telephone circuit until the extension relay is again locked up. In this arrangement, a pair of spaced contacts 25 are connected across the terminals of the trip coil 11, and when the relay is in non-signalling status, these contacts are bridged by a plate 26 carried by, although insulated from, the latch 7. Furthermore, in the modified arrangement, one terminal of the trip coil 11 is connected directly to the line conductor L-1 beyond the receiver winding 14.

Assuming that the relay 1 has been locked up in response to ringing current, the resulting turning movement of the latch 7 into the position of Fig. 2 will unbridge the contacts 25, thereby establishing a direct circuit from the line conductor L-1 through the trip coil 11 to the hook contact 15. Therefore, lifting of the receiver R to the position of Fig. 3 will result in the passage of transient talking current directly through the trip coil 11, independently of the receiver winding 14. However, the resulting unlatching of the armature 3 will quickly again bridge the contacts 25, so that by the time the receiver hook 16 has reached the position of Fig. 4, in engagement with contacts 17 and 18, the trip coil will have been entirely shunted out of the talking circuit, as indicated in Fig. 6.

Referring now to Figs. 7 and 8, there is shown in detail the mounting of the hook controlled contacts of Fig. 1 within the base of a telephone subscriber's set, the outlines of the instrument and base being indicated in dot and dash lines.

In Fig. 7, the hook 16, shown diagrammatically in Fig. 1 is in the form of a spring pressed plunger 27 which is held down in the position shown by the weight of the combined receiver R and transmitter TR, as indicated. The lower end of the plunger 27 carries a pair of spaced contacting actuating plates 28 and 29 of insulating material, which plates bear upon the contact fingers 16a, 16b and 16c, corresponding collectively to the movable hook 16 in Fig. 1. The several contacts 15, 17 and 18 are represented by the correspondingly designated short contact fingers, and the sequence of operation is such that upward movement of the hook 16 upon removal of the receiver will result in successive engagement of the con-

tact pairs 16a-15, 16c-18 and 16b-17 in the order named.

As shown in Fig. 8, the trip coil contacts 16a and 15 are mounted on an insulating block 30, 5 displaced from a similar insulating block 31 which carries both pairs of instrument contacts 16b-17 and 16c-18. Obviously, other contact arrangements can be employed within the base of a standard subscriber's set for accomplishing the results described above, the particular showing of Figs. 7 and 8 being merely an illustrative embodiment of one way of carrying out the invention.

From the foregoing then, it is obvious that by the present invention there is provided an improved control circuit for telephone extension signals and the like, whereby a circuit which is locked in a given signalling status by telephone ringing current is automatically restored to non-signalling status by transient talking current in immediate response to the removal of a conventional telephone receiver from its hook at the subscriber's set being called.

I claim:

1. A control circuit comprising in combination, 25 a source of telephone ringing current, a separate source of electrical energy, an electrical signalling device, means for employing telephone ringing current to lock said electrical device in continuous signalling status and means automatically responsive to transient telephone talking current for placing said device on a non-signalling status.

2. A control circuit comprising in combination, 35 a source of telephone ringing current, a separate source of electrical energy, an electrical signaling device, means for employing telephone ringing current to lock said electrical device in continuous signalling status and means automatically responsive to lifting of a telephone receiver for placing said device on a non-signalling status.

3. A control circuit comprising in combination, 45 a source of telephone ringing current, a separate source of electrical energy, an electrical signaling device, means for employing telephone ringing current to lock said electrical device in continuous signalling status and means automatically responsive to the lapse of a predetermined time interval following the response to ringing current, for placing said device on a non-signalling status.

4. A control circuit comprising in combination, 55 a source of telephone ringing current, a separate source of electrical energy, an electrical signalling device, means for employing telephone ringing current to lock said electrical device in continuous signalling status and means automatically responsive to lifting of a telephone receiver for placing said device on a non-signalling status, said circuit also providing means for placing said device on a non-signalling status, in the event that said receiver is not lifted within a predetermined period following the response of said device to ringing current.

5. A control circuit comprising in combination, 65 a source of telephone ringing current, a separate source of electrical energy, a telephone extension signal normally in non-signalling status, means for employing telephone ringing current to lock said signal in signalling status, with respect to said separate source, and means responsive to the flow of transient telephone talking current to unlock said signal.

6. A control circuit comprising in combination, 70 a source of telephone ringing current, a separate source of electrical energy, a telephone extension signal normally in non-signalling status, means

for employing telephone ringing current to lock said signal in signalling status, with respect to said separate source, and means responsive to removal of a conventional telephone receiver from its hook to unlock said signal.

7. A control circuit comprising in combination, a source of telephone ringing current, a separate source of electrical energy, a telephone extension signal normally in non-signalling status, means for employing telephone ringing current to lock said signal in signalling status, through its connection to said separate source, and means responsive to the manual operation of a conventional telephone instrument for the purpose of answering a call, to restore said signal to its non-signalling status by disconnection from said separate source.

8. A control circuit comprising in combination, a source of telephone ringing current, a separate source of electrical energy, a telephone extension signal normally in non-signalling status, means for employing telephone ringing current to lock said signal in signalling status through its connection to said separate source and means responsive to lifting of a telephone receiver for unlocking said signal, said circuit also providing means for restoring said signal to its non-signalling status, in the event that said receiver is not lifted within a predetermined period following the response of said signal to ringing current.

9. A control circuit comprising in combination, a source of telephone ringing current, a separate source of electrical energy, a telephone extension relay for normally maintaining an associated signal in non-signalling status, said relay being responsive to ringing current to energize said signal from said separate source, means for locking said relay in signalling status, and means responsive to the flow of transient telephone talking current to unlock said relay and restore said signal to non-signalling status.

10. A control circuit comprising in combination,

a source of telephone ringing current, a separate source of electrical energy, an electrically operated signal, a telephone extension relay for normally maintaining said signal in non-signalling status, said relay being responsive to ringing current to energize said signal from said separate source and lock itself in signalling status, and means comprising relatively movable contacts incorporated in the base of a conventional telephone instrument for unlocking said relay in response to the removal of the receiver of said instrument.

11. A control circuit comprising in combination, a source of telephone ringing current, a separate source of electrical energy, an electrically operated signal, a telephone extension relay for normally maintaining said signal in non-signalling status, said relay being responsive to ringing current to energize said signal from said separate source and lock itself in signalling status, and means comprising relatively movable contacts incorporated in the base of a conventional telephone instrument for utilizing transient telephone talking current to unlock said relay, as soon as the receiver of said instrument is lifted.

12. A control circuit comprising in combination, a source of telephone ringing current, a separate source of electrical energy, an electrically operated signal, a telephone extension relay for normally maintaining said signal in non-signalling status, said relay being responsive to ringing current to energize said signal from said separate source and lock itself in signalling status, and means comprising relatively movable contacts incorporated in the base of a conventional telephone instrument for utilizing transient telephone talking current to unlock said relay, as soon as the receiver of said instrument is lifted, with said unlocking means being thereafter maintained out of the talking circuit of said instrument.

JOHN H. WHEELOCK.
